Frederick Davis and William Ashdown, of Baltimore, Md.
Letters Patent.

The Schedule referred to in their Letters Patent and making part of the same containing a description in the words of the said Frederick Davis and William Ashdown themselves of their improvement on George W. Cleaveland's improvement on Rail Road Cars.

It is all to whom these presents shall come. We it known that the Frederick Davis and William Ashdown of the City of Baltimore and State of Maryland have invented a new and useful improvement on George W. Cleaveland's improvement in the Rail Road car which was patented to him in the fall of 1830. And that the following drawing, and remarks are a full and accurate description of said improvement. The object of our improvement is to produce regularity in the motion and vibration of the wheels on the rail, or prevent their liability to move in a zig-zag line, or to prevent the constant liability of the flanges of the wheels running into contact with the rails. Instead of a solid axle Mr. Cleaveland has his separated in the middle. The square frame fig 1. represents a mechanical contrivance which supports the inner end of each pair of axles, and allows both to vibrate horizontally, and they revolve independently of each other; whilst they always remain parallel with each other. The dotted lines and the seal a. show where one of the inner guides of each axle rests. The guides of the other are to be on the opposite side. Fig 2. represents the working parts of fig 1. showing the same pieces in both figs. B. is a pivot bar the rounded end of which rest in the inner holes of the bases or planes a, b, c. when by means of the bar the bar is moved to the right hand or forward, the bar c. is moved to the left or backwards. Fig 3. represents the connection of our apparatus with Mr. Cleaveland's. by means of the elevation of the pin through the middle. We make the pin fast to the lever as may be done by the square frame, & then by a square end at the top we attach the lever c. which works with the pin and pivot bar. If any desire of rods connected with c. by working joints. Fig 4. Represents a top view of the centre part of the bar. The dotted lines represent the relative position of the axles on a

armed Road, the outer and larger curve or track being from year to year, as shown in Fig. 1. It has an brace, as at 1, in Fig. 8, which is on rods connected with the levers, h, h, and the bent levers, k, k, l, by arrating joints. The bent levers at m, m, have working joints by means of bolts, in the pack, on the end of each of the bent levers at n, is an upright fixed pin as a medium of connection with other cars or moving forces. When either of the bent levers move in the direction of the arrow, by means of its connection with car, other moving force, the inner end of the arms, as at o, o, are brought man together. When each set of the levers and axles are on the same line as H, each other the car is in a position for a straight track, and by throwing the axles into a position opposite to that in which they now stand the car will be in a position for opposite curves. By the use of our fixtures, the flanges of the cars will be kept almost, if not quite at all times from from the rails, as these levers draw the car on a line of the chord of the curve or nearer to the inner track, whereas without this provision, the car will roll by means of the rubbing of the flanges against the outer rail. The traction of the forward force has a tendency to keep the car on the inner lines and consequently no tendency will remain to produce an irregular, zig-zag direction in the running of the car. Declining the apparatus for the purposes of governing and regulating the motion of the axles, our wheels as above described.
